UNITED STATES PATENT OFFICE.

ALFRED OLIN HISCOCK, OF PALATKA, FLORIDA.

COMBINED MUFFLER AND OIL-GAS PRODUCER.

1,078,353.

Specification of Letters Patent. Patented Nov. 11, 1913.

Application filed February 8, 1913. Serial No. 747,108.

To all whom it may concern:

Be it known that I, ALFRED O. HISCOCK, a citizen of the United States, and a resident of Palatka, in the county of Putnam and State of Florida, have made certain new and useful Improvements in Combined Mufflers and Oil-Gas Producers, of which the following is a specification.

My present invention relates to combined mufflers and oil-gas producers, particularly adapted for connection within the exhaust pipe of an internal combustion engine, my object being to provide a simple and inexpensive construction whereby the functions generally presented in such a device may be readily and effectively accomplished.

Other and further objects, and the advantages arising therefrom, will be apparent from the following description, in which reference is made to the accompanying drawing in which—

Figure 1 is a central longitudinal section through the device, illustrating the connections thereof in diagram. Fig. 2 is an end view. Fig. 3 is a detail transverse section taken therethrough substantially on the line 3—3 of Fig. 1.

Referring now to these figures, I provide a generally cylindrical casing A which is hollow and closed by end plates A' and A'', the latter of which is provided with a central tube a, and the former of which is provided with a central tube a' with a series of apertures a² extending around said tube. The outer portions of the tubes a and a' are internally threaded for connection with portions of the exhaust pipe of an internal combustion engine (not shown). The casing A is also provided with an annular series of openings a³ adjacent the end piece A', and against the inner surface of this end piece is disposed a rotatable valve disk C, having a circular series of apertures c² whereby communication with the interior of the casing through the end openings a² and the casing openings a³ may be controlled.

As seen particularly in Figs. 1 and 2, the casing end A' is provided with a segmental slot a⁴ and a disk C is provided with a stud c³ outstanding through the slot a⁴ and constituting a handle whereby the position of the valve disk may be readily changed.

Disposed within the casing A is a tubular core D, comprising a plurality of sections D', D² and D³, and each of the sections is provided with outstanding flanges, certain

of which are indicated by the letters d and are provided with a circular series of apertures d' and a plurality of lugs d², these flanges being of such a size that the lugs d² extend into contact with the inner surface of the casing. The other flanges indicated at d³ are adapted to abut certain of the flanges d. Extending through the core D is a tube E, the ends of which extend beyond the end flanges d of the core and are externally threaded to receive the disks e which bear against said end flanges. The several abutting flanges d, d³ and the end flanges d and abutting disks e have their inner adjacent faces hollowed out into substantially concavo-convex form in order to provide annular chambers in which are disposed reticulated diaphragms F which thus extend transversely of the core D and receive the tube E therethrough. The disk e therefore forces the several sections of the core tightly together and locks the same in position, gasket rings f being positioned between the contacting portions of the several flanges and disks.

The core D is provided with liquid fuel through an intake pipe G, leading from a fuel supply pipe G' and provided with a controlling valve g therein. From the core D, and adjacent relatively the opposite end thereof from the inner pipe G leads an outlet pipe H which may have communication either with the engine pipe H' or with a branch pipe H² entering into the casing A at one end thereof, this communication being controlled by a three-way valve H³ disposed at the junction of these pipes. Thus in starting the operation of the parts, and with the three-way valve H³ turned to connect the outlet pipe H with the branch pipe H², the valve disk C is positioned so as to register its openings c and c² with the casing and the end openings a³ and a², causing a continuous draft through the casing and the outer portion of the exhaust pipe, and liquid fuel is admitted through the intake pipe G by opening the valve g. Thus the liquid fuel runs through the core D and through pipe H and branch pipe H² into the casing A where the fuel is ignited by means of a torch or other instrumentality inserted through the draft openings and the subsequent combustion within the casing or cylinder heats the core D and accomplishes vaporization of the liquid fuel flowing therethrough. As soon as vaporization is started

the three-way valve H^3 is turned to connect the outlet pipe H with the engine pipe H' , thus cutting off the branch pipe H^2 and permitting the vaporized fuel to pass to the engine. When the engine has been started its exhaust gases, outflowing through the exhaust pipe, enter the cylinder or casing A through the tube a' and in consequence pass through the tube E and the apertures d' of the several flanges d and thence outwardly through the tube a , the noise of the exhaust being muffled in such passage and the core D being maintained in a constantly hot condition so as to continue the vaporization of the liquid fuel.

It is to be understood that during the operation of the engine, the valve disk C is turned to the position indicated in Fig. 2, cutting off the supply of air to the casing or cylinder A and preventing the exhaust gases from escaping except through the natural outlet. From this it will be seen that the liquid fuel, upon entering the core D will be broken up by its passage through the diaphragms F between the intermediate flanges d and d^3 and will therefore be in better condition for vaporization, it being understood that additional sections may be added on the core within a casing of greater length, and that the core may be taken apart if desired and the sections re-arranged, in each instance bringing the diaphragms between the flanges d and disks e into action.

I claim:

1. In a device of the character described, a cylinder having apertures at one end and tubes extending from its opposite ends for connection with the exhaust pipe of an internal combustion engine, an apertured disk rotatable on the cylinder end adjacent the said apertures and adapted to control the same, a closed tubular core within said cylinder and having outstanding apertured and abutting flanges, the inner adjacent faces of which flanges are cut away to form compartments therebetween, reticulated dia-

phragms mounted within the compartments, an intake pipe leading into the core adjacent one end thereof, an outlet pipe leading from the core adjacent its opposite end, an engine vapor supply pipe, a branch pipe leading therefrom into the said cylinder, and a three-way valve at the junction of the engine pipe, branch pipe and outlet pipe and adapted to permit of the passage of fluid from the outlet pipe through the engine and branch pipes as desired. 55

2. A device of the character described comprising a cylinder having apertured ends and adapted for attachment with an engine exhaust pipe, a member forming a valve and controlling the apertures, a hollow closed core within the cylinder, apertured members extending between the core and the inner periphery of the cylinder 65 whereby to form a muffler, valved engine connections extending outwardly from the core and having a branch pipe leading into the cylinder and a valved fuel inlet pipe leading into the core, all for the purpose 70 described.

3. A device of the character described comprising a cylinder having apertured ends, a tube for attachment with an engine exhaust pipe, a member forming a valve and controlling the apertures of the cylinder, a hollow tubular core within the cylinder and comprising a plurality of sections having outstanding flanges, a tube extending through the core, disks removable on the tube to close 75 the ends of the core and to hold the several sections thereof tightly together, valved engine connections leading outwardly from the core and having a branch pipe extending 80 into the cylinder, and a valved fuel inlet pipe leading inwardly through the cylinder and into the core all for the purpose 85 described.

ALFRED OLIN HISCOCK.
